Fig. 1

Fig. 2

Fig. 3

Fig. 4

FIG. 1 is a top plan view of a reed for a reed switch showing my new design;

FIG. 2 is a side elevational view thereof;

FIG. 3 is a side elevational view thereof; and

FIG. 4 is a top plan view of a modified form of the reed described in FIG. 1 showing my new design.

The bottom plan views opposite to the top plan views of FIGS. 1 and 4 are identical to these respective figures.

The sides opposite to the sides shown in FIGS. 2 and 3 are identical to these respective figures.

The side elevational views of FIG. 4 are identical to FIGS. 2 and 3 including the sides opposite thereof.

The reeds in FIGS. 1, 3 and 4 are broken away at one end to show indeterminate length. The tongues of FIGS. 1

and 4 include areas on either side thereof concavely depressed from the planar surface.

I claim:

The ornamental design for a reed for a reed switch, as shown and described.
